BRUSH SANDER HEAD

Herman S. Newton, Temple, Tex.

Application May 6, 1948, Serial No. 25,401

6 Claims. (Cl. 51—194)

1

This invention relates to sanding drums and more particularly to rotary brush sanders.

The principal object of the invention is to provide an improvement in brush sanders of the type having alternate brushes and abrasive strips, in which the latter are replaced when worn, by the simultaneous unwinding of a plurality of strips coiled on the core of the sander. Most important however, among the objects of the invention is to simplify the construction of such a brush sander, as well as the servicing thereof, that is to say, the replenishing of used abrasive material, and thus reduce materially the original cost of the sander and the time consumed in installing and adjusting the abrasive strips.

The invention provides a belt grooved driving head having a multiplicity of annularly spaced, circular cavities receiving the ends of an equal number of longitudinally split tubes, disposed perpendicularly to the plane of the head and adapted to retain brush mountings. A retainer ring similarly equipped to receive the opposite ends of the tubes is held in position by a reel cap, the latter, in conjunction with the driving head, holding an abrasive reel on which is wound the abrasive anchoring flaps of a fabric spider. The assembly as a whole constitutes a comparatively simple arrangement in which abrasive surfaces may be quickly and expediently renewed.

With the foregoing objects in view, the invention has further reference to certain features of accomplishment which will become apparent as the description proceeds, taken in connection with the accompanying drawings wherein:

Figure 1 is a perspective view of a brush sander constructed according to the invention.

Figure 2 is a detail view of the abrasive anchoring spider.

Figure 3 is a transverse sectional view of the sander on a slightly larger scale, taken through the midsection thereof.

Figure 4 is a longitudinal sectional view thereof, and

Figure 5 is a fragmentary perspective view of the anchorage between a strip of abrasive and flap of the spider.

Continuing with a more detailed description of the drawing, reference numeral 10 denotes a driving head having a belt groove 11 therein to receive a belt by which the sanding head is driven. Spaced about the perimeter of the driving head 10 in its inner face is a multiplicity of annularly spaced, circular recesses 12 which are adapted to receive the ends of an equal number of longitudinally slotted tubes 13, the slots of the tubes fac-

2

ing outwardly. Set screws 14 enter radial holes in the head and aligned holes in the tubes 13 to secure the latter against rotative and longitudinal displacement with respect to the head 10.

Brushes 15 are of conventional manufacture and each set of bristles is anchored in a metal mounting bar 16. These mounting bars are slid longitudinally into the tubes 13, the bristles extending through the slots in the tubes, as shown in Figure 4. To insure rigidity of the brushes in relation to the tubes 13, stabilizing wedges 17 are inserted in the tubes under the brush mounting bars 16.

Opposite the driving head 10 is a retaining ring 18 having an internal bevel 19 and is provided with an annular series of circular recesses 20 corresponding to the recesses 12 in the driving head 10 and which receive the opposite ends of the brush holders or tubes 13. A cap 21, having an external bevel 22, is mounted on the spindle 23 of the mounting shaft 24 and its bevel 22 corresponds to and bears frictionally against the bevel 19 of the retainer ring 18, thus holding the latter in concentric relationship with the shaft spindle 23. The end of the spindle 23 is threaded to receive a nut 25 which holds the cap 21 compressedly against the ring 18 and otherwise maintains the parts in assembled relationship.

The driving head 10 has a boss 26 formed on its inner face which is in confronting relationship with a similar boss 27 formed on the inner face of the cap 21. These bosses serve jointly as a mounting for a reel 28 which is frictionally retained thereon with the boss 27 and cap 21 by means of a key 29, partially retained in a recess adjacent the boss 27 and extending into a slot 30 in the end of the reel 28.

In Figure 2 is shown an end elevational view of a spider, consisting of strips of fabric or other material formed into substantially U-shape to provide flaps 31. The individual strips are sewed or otherwise secured together at a to define a circular sleeve which is slid onto the reel 28 and secured thereto by brads or rivets b.

In Figure 5 is shown the manner in which strips 32 of abrasive material are secured to the flaps 31 of the spider shown in Figure 2. As shown, staples 33 are employed but it has been found that adhesive tape is equally as suitable for the purpose.

To install the abrasive strips in the head, a number of such strips are cut in predetermined length and secured at their ends, as described, to the ends of the spider flaps 31. The spider is then slid onto the reel 28 which has previously been

installed in the head. The free ends of the strips are passed between the brush mounting tubes 13, whereupon the cap 21 is mounted on the spindle 23. By inserting a suitable tool in a hole 34 in the hub of the cap 21 the latter may be rotated to turn the reel 28 to wind the extended strips 32 of abrasive material onto the reel 28 in overlapping relationship until the extremities of the strips lie on a plane with or adjacent to the ends of the brushes 15. When the desired position of the strips is obtained, the nut 25 is tightened to bring the bevel 22 of the cap 21 firmly against the corresponding bevel 19 of the retaining ring 18, thus locking all parts securely together.

When the extended portions of the abrasive strips 32 become too worn for effective use, the nut 25 is loosened and the cap 21 is rotated to unwind the strips and thus extend sufficient unused portions thereof as will meet requirement, after which the used portions of the strips are cut off. This operation can be accomplished quickly with but negligible loss of time.

What is claimed is:

1. A brush sander including a driving head having a multiplicity of annularly spaced cavities adjacent its perimeter, an equal number of longitudinally slotted tubes retained by their ends in said cavities, a brush slidably mounted in each of said tubes, a retainer ring having cavities corresponding to those of said driving head and receiving the opposite ends of said tubes, said ring further having a bevel on its inner periphery, a cap having a peripheral bevel corresponding to and bearing against the bevel of said retainer ring to secure the assembly for common rotation, a reel interposed between said head and cap and keyed to said cap, a flexible spider on said reel having radial flaps, an abrasive strip attached to each of said flaps, said abrasive strips being wound collectively in overlapping relationship on said reel and extending radially between said brushes and means for rotating said reel through the medium of said cap to effect simultaneous adjustment of said abrasive strips in relation to said brushes.

2. A brush sander including a driving head, a plurality of longitudinally slotted tubes retained at their ends in annularly spaced recesses adjacent the perimeter of said head, an internally beveled ring having recesses corresponding to those in said head and retaining the opposite ends of said tubes, a brush mounted in each of said tubes whose bristles extend through the slot thereof, a cap within and concentric to said ring having a beveled perimeter frictionally engaging the bevel of said ring to secure said head and cap for common rotation, a reel extending between said head and cap, and to which the latter is keyed, a flexible spider affixed to said reel having radial flaps, an abrasive strip attached to each of said flaps and wound on said reel, the ends of said strips extending between said tubes and brushes and means to effect rotation of said cap when disengaged from said ring to rotate said reel to collectively adjust said abrasive strips in relation to said brushes.

3. A brush sander comprising a driving head mounted on a shaft, a series of annularly spaced and longitudinally slotted tubes whose ends are retained in perpendicular relationship to the inner face of said head, a ring retaining the opposite ends of said tubes and having a beveled inner periphery, a cap having a beveled periphery engaged with that of said ring to hold the elements of said sander in rigid assembly, a brush retained in each of said tubes whose bristles extend through the slot therein, a reel disposed axially between said head and cap and rotatable by the latter, a plurality of abrasive strips having a common anchorage to said reel and wound thereon in overlapping relationship by rotation of said cap when the latter is disengaged from said ring, and whose ends protrude between said tubes and brushes and means for securing said cap against rotation.

4. A rotary brush sander including a driving head mounted on a shaft and a ring, a circumferential series of longitudinally slotted brush retaining tubes held between said head and ring, a brush in each of said tubes whose bristles extend radially through the slot therein, a cap whose periphery is in frictional contact with the inner periphery of said ring for holding the latter in concentric relation to said shaft, a reel surrounding said shaft between sand head and cap, a plurality of fabric strips joined one to the other at spaced apart points midway between their ends to define a cylindrical sleeve receivable on said reel and a plurality of radial flaps, an abrasive strip attached to each of the radial flaps of said cylinder, said strips being wound on said reel collectively in overlapping relationship through rotation of said cap in disengaged relationship with said ring and whose ends extend radially between said tubes and brushes and means on the end of said shaft for holding said cap in fixed relationship therewith.

5. A brush sander as set forth in claim 4 in which the engaging surfaces to the ring and cap are correspondingly beveled to maintain concentricity thereof in fixed position of said cap and to secure the elements of the brush sander in rigid relationship.

6. A brush sander as in claim 4, in which the head and ring are each provided with annularly spaced recesses in their confronting faces receiving opposite ends of the series of brush retaining tubes and means for securing the ends of said tubes in the recesses of said head to hold them against longitudinal and rotative displacement.
